F. MATHEWS,
LATCH FOR HOODS OF AUTOMOBILES.
APPLICATION FILED APR. 9, 1921.

1,396,704.

Patented Nov. 8, 1921.

Atty:

UNITED STATES PATENT OFFICE.

FRED MATHEWS, OF CHICAGO, ILLINOIS.

LATCH FOR HOODS OF AUTOMOBILES.

1,396,704.

Specification of Letters Patent. Patented Nov. 8, 1921.

Application filed April 9, 1921. Serial No. 459,840.

To all whom it may concern:

Be it known that I, FRED MATHEWS, a citizen of the United States, residing at Chicago, in the county of Cook and State of Illinois, 5 have invented certain new and useful Improvements in Latches for Hoods of Automobiles, of which the following is a full, clear, and exact description.

My invention relates to means for securing 10 a movable member to a stationary member and particularly to a latch for fastening the hanged sections of the hood of an automobile to the body of the same.

The object of my invention in so far as it 15 relates to automobiles is to provide a simple and comparatively inexpensive keeper element for the sections of the hood of the same, which the hook of the contractile latch, now commonly used to hold said sections down, and which can be applied with 20 equal facility to an old or a new car to prevent chattering and rattling and automatically adapts itself to the mechanical defects or differences in the construction of said 25 latches, substantially as hereinafter fully described and as illustrated in the drawings, in which:

Figure 1 shows a fragment of one of the 30 hinged sections of an automobile hood and the platform of the body of the same which is designed in section and shows in side elevation, my invention applied thereto.

Fig. 2 is a transverse vertical section of the same taken on dotted line 2, 2, Fig. 1.

Fig. 3 is a plan view thereof.

Fig. 4 is a vertical transverse section of the improved keeper, and a side view of the upper portion of the contractile hook disengaged therefrom.

Referring to the drawings, 5, represents 40 the lower edge portion of one of the hinged sections of the hood of an automobile, and 6 the plateau or platform upon which the lower edge of said hood section 5 rests when 45 it is closed.

The keeper constituting my improvement is adapted to be used in conjunction with any latch comprising a hooked member and a lower member telescopically engaging the 50 same whose lower end is secured to the platform upon which the lower edge of said hood section 5 rests when it is closed. The latch illustrated in the drawings and hereinafter described and referred to in conjunction with my improvements is typical

of them all, and it does not involve any originality.

This latch comprises a shank 7 that is hinged between pivotal lugs 8, (the supporting plate 9 of which is suitably secured to 60 the platform 6) in such manner that it can be swung toward or away from the hood section. The upper end of this shank enters and telescopically engages the tubular shaft 10 of the latch member 11, whose upper end 65 has a hook 12 projecting toward the hood and has a handle or finger-grasp 13 projecting diametrically outward therefrom, by means of which it is manipulated to raise or lower the hook. When the hook is raised 70 and moved inward on the pivot of shank 7, its longitudinal movement is resisted by a spring (not shown) incased in the tubular shaft 10 thereof, and the action of this 75 spring is constantly exerted to contract the latch and pull the hook toward the pivot of said latch.

The keeper embodying my improvements consists of a supporting-plate 25, that is secured to the section of the hood by bolts and 80 nuts 14, or otherwise, and has corresponding lugs 15, 15, projecting outwardly therefrom. These lugs have elongated corresponding co-terminous parallel bearing slots, 16, 16, 85 in them that extend from near their outer upper ends downward in an inclined direction toward the hood, and are adapted to receive the trunnions, 17, of a tumbler 18.

This tumbler consists of an oblong metallic member whose sides (from which the 90 trunnions project) are parallel. The outer portion of said tumbler is bifurcated and these bifurcations, 19, 19, are connected near their outer ends by a cross-bar 20 which is adapted to be engaged by the hook of the 95 latch, as will hereinafter be more fully explained.

The inner end of the tumbler is, preferably, curved from its upper edge to its lower edge and conforms to a quadrant of a circle, 100 and is adapted to frictionally engage the supporting-plate.

In operation, the tumbler when the hood section is closed will assume before it is engaged by the latch, the position to a greater 105 or less degree, shown in dotted lines in Fig. 4 of the drawings. When the latch is raised and moved toward the hood and the hook thereof is made to engage the cross-bar 20 of the tumbler, said tumbler will move into the 110

position shown in Fig. 1 of the drawings, and clamp against the supporting-plate and prevent vibration of the hood.

I do not desire it to be confined to the exact shape of the tumbler as it is evident it can be altered to coöperate with any type of latch that can be used in conjunction therewith, or its design changed to suit the taste of the manufacturer, without departing 10 from the principle of its construction.

What I claim as new is:

1. A keeper for a latch comprising parallel lugs a support for the same, and a rocking member journaled in said lugs one end 15 of which is adapted to be engaged and moved by the said latch to cause its opposite end to engage the support of the lugs.

2. A keeper for a latch comprising parallel lugs, a support for the same and a rocking member journaled in said lugs and bodily movable toward said support and adapted to be engaged by the said latch at one end and moved to bring its opposite end into frictional engagement with said 25 support.

3. A keeper for a latch comprising parallel lugs having corresponding inclined slots therein, a support for said lugs and a rocking member journaled in said slots and 30 adapted to be engaged by said latch at one end and moved on its axis to bring its opposite end into frictional engagement with said support.

4. A keeper for a latch that is provided 35 with a hooked end, comprising parallel lugs having corresponding inclined slots therein, a support for said lugs, and a rocking member journaled in said slots having its outer end bifurcated and the bifurcations connected by a cross-bar which latter is adapted 40 to be engaged by the hook of the latch to cause said member to move on its axis to bring its opposite end into frictional engagement with said support.

45 5. A keeper for a latch comprising parallel lugs a support for the same and a rocking member journaled in said lugs having an eye in one end which is adapted to be engaged by said latch to cause it to lock and 50 its opposite end to engage the support of said lugs.

6. The combination with a latch which is pivoted at one end to a suitable support and the opposite end of which is provided with 55 a hook, of a hinged section of an automobile hood, and a keeper pivoted mediate its ends to said hood on an axis that is parallel to the outer surface of said hood, and the inner end

of which when its outer end is engaged by the hooked end of said latch will engage 60 said support.

7. The combination with a latch comprising two spring returnable telescoping sections one of which is pivoted at one end to a suitable support and the opposite end of 65 the other section of which is provided with a hook, of a hinged section of an automobile hood, and a keeper pivoted mediate its ends to said hood on an axis that is parallel to the outer surface of said hood, and the 70 inner end of which when its outer end is engaged by the hooked end of said latch will engage said support.

8. The combination with a latch which is pivoted at one end to a suitable support and 75 the opposite end of which is provided with a hook, of a hinged section of an automobile hood, and a keeper pivoted mediate its ends on an axis that is parallel to the outer surface of said hood, which has an eye in its 80 outer end portion, that is adapted to be engaged by the hooked end of said latch to cause its opposite end to engage said support.

9. The combination with a latch comprising 85 two spring returnable telescoping sections one of which is pivoted at one end to a suitable support and the opposite end of the other section of which is provided with a hook, of a hinged section of an automobile 90 hood, and a keeper pivoted mediate its ends on an axis that is parallel to the outer surface of said hood, which has an eye in its outer end portion, that is adapted to be engaged by the hooked end of said latch to 95 cause its opposite end to engage said support.

10. The combination with a latch which is pivoted at one end to a suitable support and the opposite end of which is provided 100 with a hook of a hinged section of an automobile hood, lugs projecting from the outer surface thereof having downwardly and inwardly extending elongated openings therein, and rocking keeper having trunnions 105 that are journaled in said elongated openings and having an eye in its outer end that is adapted to be engaged by the hooked end of said latch to cause its opposite end to engage said support.

110 In testimony whereof, I have hereunto set my hand.

FRED MATHEWS.

Witnesses:

FRANK D. THOMASON,
VIOLET WARDELL.
